UNITED STATES PATENT OFFICE

149,592

DESIGN FOR A LAMP

Frederick Schwartz, Chicago, Ill.

Application April 14, 1947, Serial No. 138,350

Term of patent 7 years

(Cl. D48—20)

To all whom it may concern:

Be it known that I, Frederick Schwartz, a citizen of the United States and resident of Chicago, in the county of Cook and State of Illinois, have invented a new, original, and ornamental Design for a Lamp, of which the following is a specification, reference being had to the accompanying drawing, which is a perspective view of a lamp, showing my new design.

I claim:

The ornamental design for a lamp, substantially as shown.

FREDERICK SCHWARTZ.
